RAZOR BLADE CONDITIONING DEVICE

Charles L. Willcox, Atlanta, Ga.

Continuation of application Serial No. 95,936,
March 19, 1926. This application November 12,
1927, Serial No. 232,898. Renewed August 10,
1934

9 Claims. (Cl. 51—80)

The invention relates to improvements in devices for conditioning razor blades, and more particularly to a device such as shown and described in my copending application Ser. No. 95,936 filed March 19, 1926, of which this application is a division.

An object of the invention is to provide a device of the above type with means for holding the blade in fixed position and in contact with the rollers for honing.

10 A further object of the invention is to provide a device of the above type wherein the holding means holds the blade flexed and the edges thereof in firm contact with the conditioning rolls.

15 A further object of the invention is to provide means of the above type which may be used for bringing about a pressure on the blade being honed directly in the region of the honing of the same.

20 A further object of the invention is to provide a device in which a resilient pressure is maintained upon the blade edges being honed that is greater than attainable by the elasticity of the blade itself.

25 The invention has been presented on the accompanying drawings in two illustrative forms of execution, with these and other objects in view as will appear in the course of the following specification. One of these forms is of a substantially rigid type, while the other is a folding device.

In the accompanying drawings:

Figure 1 is a perspective view of a conditioning device according to this invention as employing with double edged blades of the Gillette type, and having a rigid frame.

Fig. 2 is a cross section on line 2—2 of Fig. 3, on a larger scale.

Fig. 3 is a longitudinal section on line 3—3 of Fig. 2, on the same large scale.

Fig. 4 is a detail of the end assembly of the device.

Fig. 4a is a section on the line 4a—4a of Fig. 1.

Fig. 5 is a plan view of a modified form employing a collapsible frame.

Fig. 6 is an end view of the device of Fig. 5, on a larger scale.

Fig. 7 is a section on line 7—7 of Fig. 5.

Fig. 8 is a section on line 8—8 of Fig. 5.

50 In the forms of execution of Figs. 1 to 4a a rigid frame has supported thereon the several dressing surfaces, which frame is made from sheet metal blanks punched and folded into the shape represented. A base plate 10 has formed therewith the flat flanges 11 and the projecting

lateral members 12 which at their ends are respectively folded inward toward each other and present the portions 13, 13 in alinement. An end plate 15 is placed upon these members 13 and is provided itself with the rearwardly extending blade support 21 and the belt supports 23, 23a, 23b. It will be noted that the base plate 10 is formed integral with the flanges 11 and members 12, while the end plate 15 is formed integral with the blade support 21 and the belt supports 23, 23a, 23b. The end plate 15 is held rigidly with respect to the members 13 by a U-shaped bolt 16. This bolt passes through apertures adjacent the ends of the base plate 10 and extends inside of and in parallelism with the projecting members 12, and finally through apertures in the portions 13 and the end plate 15, and is secured rigidly in place by the nuts 17 on its threaded ends.

20 A finishing dressing stone 18 having a flat top surface is provided with a reduced end or roller 20 which is adapted to extend underneath the flange 11. The housing 18a has a peripheral groove 19 extending around three sides for the reception of a U-bolt 16 on the exterior of the 25 housing and this forms a flange on the interior of the housing which supports the dressing stone. The housing 18a is provided with a short lip 18b centrally thereof, and at its upper edge which is adapted to engage a recess 18c in the stone 18. 30 This holds the outer end of the stone in the housing and the reduced portion extending underneath the flange holds the inner end of the stone in the housing. Thus it is that the stone rests firmly on the flange and is held in place on the housing when the parts are assembled. This housing 18a is further provided at the end received within the flanges 11 with tongues 21x extending out of the plane of the metal housing to fit over and support a U-shaped member 21a, 40 21b of spring wire for the purpose indicated hereinafter. It will be understood that when the U-shaped bolt 16 is in position and its nuts 17 have been tightened down, this bolt draws the housing 18a into a rigid position between the 45 flanges 11 and thus holds the dressing stone 18 in its proper position; and by the rabbet 20 of the stone 18, the stone is held in position by the upper flange 11 with its top surface above the top surface of the flange 11, so that in dressing a 50 blade in the stone 18, the blade does not come in contact with the metal flange 11.

The blade support or brace arm 21 and the belt supports 23, 23a, 23b are preferably formed integral with the end plate 15, and extend rear- 55

ward and are joined to the base plate 10 and the flanges 11 as shown in Fig. 3, preferably by soldering or welding so that the frame constituted by the base plate 11 and the end plate 15 and 5 their integral parts form a single structure of great strength and rigidity.

The dressing rollers 24, 25 are loosely mounted on the shafts 26, and are composed of abrasive material and present continuous rigid unyielding 10 surfaces for honing the blade. In devices already constructed I have employed rollers formed from natural and artificial stone, and have found that such materials as carborundum and a material called "artificial slate" by reason of its 15 dark slatey color and the material of which it is composed, are excellently adapted to the purpose: but it will be understood that the device is not limited to such rollers but that any other abrasive agent may be employed, and preferably 20 one providing a non-yielding surface for operation upon the edge of the blade. The roller surfaces are cylindrical, and have been illustrated in the drawings of Figs. 1 to 4 as being formed with relieving grooves 25g extending spirally 25 about the respective rollers. It will be understood however that from certain aspects of the invention a smooth roller may be used.

The shafts 26 for these rollers pass through bushings 26a placed in the rollers and fastened 30 thereto so that a metal to metal bearing is formed. The shafts 26 are journaled in apertures of the base plate 10 and of the members 13 and the end plate 15, and are held rigidly in position as shown in Fig. 4. In this figure a latch 26x has an aperture adjacent one end fitting around the bolt 16 beneath the nut 17 thereof. Its other end is formed to fit within a notch 26n in the end of the shaft 26. It will be understood that when the nut 17 is loosened, the latch 26x can be rocked counter-clockwise about the bolt 16 until the 40 shaft 26 is free. The shaft 26 may then be withdrawn from its journals and from the bushing 26a so that the rollers may be immediately withdrawn. When the respective roller is replaced in 45 position, the shaft 26 may be reseated, the latch 26x rotated back to the position shown in Fig. 4, and then when the nut 17 is tightened down, the latch 26x will be held fixedly in position.

Each of these rollers 24 and 25 has associated 50 therewith a ratchet wheel 24a or 25a, which as shown in Fig. 2, is in operative engagement with a respective pawl 24b or 25b. The respective pawls 24b, 25b are journaled about the arms of the U-bolt 16, and are limited in their relative 55 rocking movements by engagement with the projecting members 12 of the frame. It will be understood that the pawls engage around the bolt 16 for more than half of its periphery. Along 60 its length, the bolt 16 is provided with a cut-away portion 16a (Figs. 2 and 3) which permits the pawl to be withdrawn from the bolt 16 by sliding the pawl along the bolt until the notch 16a is 65 reached. It will be understood that normally the pawl is retained against such sliding movement by its engagement between the base plate 10 on the one hand and the projecting portions of respective rollers 24 and 25 on the other hand, as shown in Fig. 2.

The bearing bushing 26a for each roller extends 70 beyond the end of the roller at the rearward end, that is the end adjacent the base, and mounted on this projecting end of the bushing is a washer 25x and a ratchet 25a. The ratchet and the washer fit tightly on the bushing so as 75 to turn with the bushing and the bushing turns

with the roller. As a further means for joining the ratchet and the roller I have provided an anchor pin 1. This anchor pin passes through the ratchet and into the roller and lies between the bushing and the outer surface of the roller. 5 The bushing at the other end of the roller also projects in order to form a reduced bearing to hold the end of the roller away from the member 13. This reduces the frictional contact between the roller and the member 13. This is all 10 clearly shown in Figure 3 of the drawings.

A U-shaped spring member 27a, 27b extends through small apertures in the base plate 10 and has its ends curled slightly toward the center plane of the structure, and received within 15 notches on the respective pawls 24b, 25b, as shown in Fig. 2. It is preferred to have the forward ends of this U-shaped spring bent inward as shown in Fig. 2 to assist in retaining the pawls 20 in their proper position. These spring ends 27a, 27b serve to force the respective pawls into engagement with the respective ratchets.

The upper surface of the braces or belt supports 23, 23a, 23b are rounded so as to smoothly 25 guide the belt 28 with respect to the frame. These belt supports are in such relationship to the lower generatrices of the rollers 24 and 25 that the belt must pass in a zigzag direction 30 from brace to roller and back to another brace, whereby a sufficient driving friction is obtained for the purpose intended.

The driving strap or belt 28 is passed over the brace 23a, beneath the roller 24, over brace 23, beneath the roller 25 and out over brace 23. It will be understood that one end of the driving 35 strap is customarily secured to a wall hook or the like and the other is held in the operator's hand during use. This driving strap 28 may be of leather, fabric or other flexible material: it does not come into contact with the razor blade 40 and hence any such material may be employed.

The brace 21 has upstanding lugs 30 thereon to fit the central apertures of double-edged razor blades of the Gillette type, in the particular illustration represented: when a blade is first laid 45 about these lugs 30, it rests at its cutting edges upon the dressing rolls and is free of the brace 21 itself. Each of the lugs 30 has a rearwardly directed notch 30a adjacent the brace 21; the upper walls of the notches being substantially 50 in a plane parallel to the brace 21 and below the plane of the upper surface of a razor blade intended to engage therewith when such razor blade is first placed about the lugs 30.

A spring retaining plunger 32 is mounted at 55 the end of a straight wire spring 33. The spring plunger 32 is guided in an opening 34 in the brace 21, and the spring 33 extends beneath and substantially parallel to the brace 21 and is secured at its forward end 35 to the lower surface of the brace 21, for example by soldering or welding. The forward upper edge of the plunger 32 is beveled away at 36, and the forward substantially vertical edge of the plunger 32 is spaced respectively from the vertical walls of the notches 30a 60 by distances equivalent to the respective distances from the end of a blade to the corresponding edge of the central apertures therein.

It will be seen that the device is simple and compact, and that by the assembly it is possible 70 to remove and replace the rollers and belts without dismounting the U-bolt 16.

The operation of the represented device in dressing a double edged safety razor blade of the 75 flexible type referred to is as follows: a double

edged blade **B** is placed about the lugs **30**, with its edges resting upon the cylindrical surfaces of the rollers **24** and **25**. In the preferred operation, a second and similar blade **BB** is placed over this first blade, and the stack of blades thus formed is pressed downward along its central axial line until the lower surface of the lower blade **B** is substantially in contact with the upper surface of the brace **21**. During this operation the rearward end of the lower blade forces the spring plunger **32** downward against the resiliency of its spring **33**. A finger of the operator is then employed to slide the stack of blades forward in a direction parallel to the brace **21** whereby they are engaged in the notches **30a** until finally the rearward end of the stack of blades is disengaged from the plunger **32**, which flies upward behind them and holds the stack of blades fixedly in position as shown in Fig. 2, so that the resiliency of both blades provides a working pressure relatively between the lower surface of the cutting edges of the lower blade and the respective dressing rolls **24a**, **25a**. It is preferred to have the upper wall of the respective notches **30a** at a distance from the upper surface of the brace **21** which is greater than the thickness of two blades, so that the sliding action is free, and whereby it is possible to produce a slightly greater curvature of the blades after being placed in the device, by a finger pressure along the central radial line of the top blade.

By the employment of such a stack of blades, it is possible to obtain a greater pressure at the surfaces being honed than can be gotten with a single blade, having due regard to the proper angular presentation of the dressing rollers, and to the strains upon the blades themselves. It is evident that although a stack of two blades is employed illustratively, the device may in practice be manufactured for a stack of any number, as any person skilled in the art can calculate the proper angles and pressures after having given the size of and specific properties of the material of the blades.

The operator then draws the driving belt or strap **28** taut and moves the device along the strap from one end toward the other, and back again. While the device is moving toward the left in the position shown in Fig. 2, the roller **24** is held against rotation by the pawl **24b** in engagement with the ratchet wheel **24a**. The roller **25** is, however, free to move, since its ratchet wheel and pawl have a permissible movement with respect to each other: it therefore is rotated by the strap **28** and the surface of this dressing roller is so moved, in this illustrative example, that the direction of dressing is from the center of the blade toward the cutting edge, and it will be understood that the roller will tend to produce a concavity in the safety razor blade at its edge. As the device moves in the opposite direction or toward the right in Fig. 2, the roller **25** will be held stationary by its pawl **25b** and ratchet **25a** and the roller **24** will be free to rotate, and this in turn will then produce a concavity on the same side of the razor blade but at the opposite edge.

It is found in practice that two or three strokes in each direction will recondition the usual blade. Thereupon the spring plunger **32** is depressed, and the stack of blades is pushed rearwardly with the finger until disengaged from the notches **30a**: the stack is then removed, turned upside down and replaced, and the outer surface of the blade **BB** is now dressed, under the resilient pressure of both blades. The stack is then removed again,

and the outer surfaces brought together, and the formerly inner surfaces are dressed similarly.

The razor blades have now been honed to concavity, and are ready for finishing. This is accomplished individually on a flat finishing surface of the stone **18**, by placing the flexible blade thereon as at **Ba** and bearing down with the fingers upon the blade adjacent its edges. It has been found in practice that, by moving the blade lightly about upon the flat surface, the edges are quickly brought to an excellent condition for smooth shaving, and that a true and accurate cutting edge is produced.

The device may also be employed, with or without the brace **23**, by reciprocating the device on a suitable surface such as the palm of the hand, so that the surface comes into contact with the rollers to successively actuate them in the desired directions.

In the modified forms of Figs. 5 to 8, the assembly of the base plate **10** with the flanges **11** and side members **12** is substantially the same as before: together with the provision of the end plate **15** with the respective belt guides or braces **23**, **23a**, **23b**, and the blade holder **21** with the lugs **30**. The U-shaped bolt **16x** is of the same general type except shorter, and in this modified form likewise passes through the end plate **15** and the base plate **10**. The rollers **24**, **25** are received as before on shafts **26** and are provided with the respective ratchets **24a**, **25a** engaging with the pawls **24b**, **25b**. The belt **28** is passed with respect to the belt guides **23**, **23a**, **23b** and the rollers **24** and **25** as before. A ring **R** is provided at the end for suspending the device from a wall hook or nail when not in use.

In this modified form, however, the flanges **11** and base plate **10** receive an end plate **40** having a groove **41** therein for the reception of the bight of the U-bolt **16x**. This plate **40** likewise has the downwardly extending fingers **42** with prongs **43** at the ends thereof to be received within notches in the finishing stone **18x** to hold this stone in position. The end structure comprising the end plate **15** is likewise formed with downwardly extending fingers **44** having prongs to engage notches in the other end of the finishing stone **18x**. In this way, the stone **18x** is supported rigidly on the bottom of the device against movement in any direction, and may be released by disengagement of the bolt **16x**, which in this case as before serves to hold the various parts together. It will be noted that the stone rests on the braces **23**, **23a**, **23b** and thus receives a further assurance against dislocation.

The handle in the present modified form comprises a strip of metal bent at its ends into parallelism with the adjacent part of the metal as shown at **50** in Fig. 5. The general shape of the handle is that of a **W** with the bight **51** passing across the rear of the device when closed (Fig. 5). When the handle is drawn out to the position **52** shown in dotted lines in Fig. 5, the end portions **50** engage around and over the extended guide loops **53**, and by their resilient grasping of these loops hold the handle in extended position. The guide loops **53** are formed by a band of material **54** located between the flanges **11** (Figs. 7 and 8) and held fixedly thereto by the location of the side members of the handle **51** between the loops **53** and the guide plate **56** formed by bending the outer ends of the transfer stiffener **56** which extends across the rear of the device in parallelism to the base plate **10**.

In operation, when the device is removed from

its box, the handle 51 is drawn out into the position shown in dotted lines in Fig. 5. When the handle is drawn completely out, these ends 50 engage resiliently with the loops 55a to hold the handle 51 in position. One end of the strap 28 may now be engaged with a wall hook and the other held in the hand and the device drawn back and forth as before. To insure a firm grip of the hand in operating the machine over the driving belts the rebent ends are knurled or roughened.

When it is desired to replace the device in its box, the handle is forced inward into the position shown in full lines in Fig. 5. The strap 28 adjacent the metal end clip 60 is then passed through the rebent end 50 adjacent the roller 24 (Fig. 6) and the strap drawn down so that the metal clip 60 rests lightly on the roller 24. The other end of the strap as it projects from the brace 23b is turned downward and wrapped around the lower face of the finishing stone 18x and then passed entirely around the device, through the metal ring 61 which is pivoted in the metal end clip 60. The portion of the belt adjacent the other rebent end 60 is passed beneath this end so as to hold the belt fixedly in position. It is preferred to have at this end of the belt a similar metal clip 62 receiving a cord 63. This cord is then passed through the ring 61, which may be bent upward into a vertical position as shown in dotted lines in Fig. 6, for this purpose. The middle of the cord 63 is then folded over and around the ring 61 (see Fig. 5) and then the ring 61 is forced into the position shown in Fig. 6 when the belt is held fixedly in position protecting both rollers and a large portion of the finished surface 18x. This is a particularly convenient form of wrapping the device for transportation.

It will be understood that these illustrations are not limitations of the invention, and that the latter may be employed in many ways within the scope of the appended claims.

Having thus fully described my invention, what I claim as new and desire to secure by Letters Patent, is:—

1. In a conditioning device for razor blades, a frame having a base and an end with supports therebetween, a rotatable dressing roller journaled in said frame, a ratchet fixed to said roller, a blade alining member to support a blade in working position with respect to said roller, a U-bolt passing through said base and end to clamp the same together, a pawl pivotally mounted on said U-bolt and having a notch eccentric to its axis, and a spring projecting from said base plate substantially parallel to the axis of the pawl and engaged in said notch, said spring maintaining said pawl in engagement with said ratchet.

2. In a conditioning device for razor blades, a frame having a base, a rotatable dressing roller journaled in said frame, a ratchet of lesser diameter than said roller and fixed thereto adjacent said base, a blade alining member to support a blade in working position with respect to said roller, a pivot member upstanding from said base and having a notch therein at a distance from said base, a pawl mounted on said pivot and having a portion thereof cut away complementary to said notch and extending less than 180° around the periphery of said pivot, said pawl being maintained in engagement with said ratchet between the end of the roller and the base, said pawl being movable from its operative position along the said pivot to the location of said notch so that

the pawl may be withdrawn from the pivot at the notch.

3. In a conditioning device for razor blades, a frame comprising separable elements, a shaft passing through apertures in said frame, a conditioning roller journaled on said shaft, a blade alining member to support a blade in working position with respect to said roller, a clamping bolt passing through said members, a latch pivoted on said bolt and having one end adapted to enter a notch in said shaft to secure the same against withdrawal from said frame, the nut of said bolt drawing said members together and holding said latch against movement.

4. In a conditioning device for razor blades, a frame, blade holding and conditioning devices mounted on said frame, loops on said frame, a U-shaped handle slidable in said loops between collapsed and extended positions, and rebent ends on said handle to frictionally engage with the loops to prevent removal of said handle from the frame and to hold said handle in extended position.

5. In a conditioning device for razor blades having a rigid frame, a rotatable dressing roller journaled in said frame, and a blade alining member mounted on said frame, including upstanding lugs to be received in the central holes of a double-edged razor blade, said lugs being provided with undercuts affording an overhanging ledge to engage the blade and hold it in contact with the dressing roller, the combination of maintaining means to hold the blade engaged in the undercuts including a resiliently mounted member to prevent endwise disengaging movement of the blade when engaged in said undercuts, said member being adapted by its resilient mounting to move to a position such that the blade may be slid endwise into and out of the undercuts for placing or removing the blade with respect to said upstanding lugs.

6. In a conditioning device for razor blades having a rigid frame, parallel rotatable dressing rollers journaled in said frame, a bridge mounted on said frame and located between said rollers, and upstanding lugs mounted on said bridge and provided with undercuts whereby to hold a double-edged blade with central apertures in position upon said rollers, the combination of a plunger and spring mounting means to hold the plunger normally in position above the bridge, said spring mounting means being located relatively beneath the bridge so that the upper surface of the bridge is clear of incumbrance, said plunger when in its normal position being adapted to engage with the end of the blade whereby to prevent withdrawal of the blade from the undercuts in said lugs, and adapted when depressed against the action of its spring mounting means to be free of the blade whereby the blade may be withdrawn from the undercuts.

7. In a conditioning device for razor blades having a rigid frame, parallel rotatable dressing rollers journaled in said frame, a bridge mounted on said frame and located between said rollers, and upstanding lugs mounted on said bridge and provided with undercuts each affording an overhanging ledge, said lugs being adapted to pass through the central apparatus of a double-edged razor blade and hold the same in alignment upon said rollers, the said ledges being located below the tangent plane of the rollers, whereby the razor blade when in position is held flexed, the combination of a plunger and spring mounting means to hold the plunger normally in position

above the bridge, said spring mounting means being located relatively beneath the bridge so that the upper surface of the bridge is clear of incumbrance, said plunger when in its normal

5 position being adapted to engage with the end of the blade whereby to prevent withdrawal of the blade from the undercuts in said lugs, and adapted when depressed against the action of its spring mounting means to be free of the blade 10 whereby the blade may be withdrawn from the undercuts.

8. In a device for reconditioning razor blades, a frame, a pair of parallel abrading rolls journaled in said frame, a blade holding support on 15 said frame between the rolls and means carried by said blade holding support for clamping a plurality of superposed blades under a bowed stress with the opposite cutting edges of the

lowermost blade in appropriate bearing pressure respectively against the peripheries of said rolls, whereby the cutting edges are reconditioned upon rotation of the rolls.

9. In a device for reconditioning razor blades, a frame, a pair of parallel abrading rolls journaled in said frame, a stationary blade holding support on said frame between the rolls and means for centrally and rigidly clamping a razor blade on said holding support under a bowed stress with the opposite cutting edges of the razor blade under bearing pressure respectively against the peripheries of said rolls, and a blade providing a reinforcement for the razor blade and correspondingly therewith clamped upon 10 15 said support.

CHARLES L. WILLCOX.
